ADJUSTABLE HEADREST

John T. Armbruster, Niagara Falls, N.Y., assignor to American Optical Corporation, Southbridge, Mass.

Filed Dec. 7, 1972, Ser. No. 313,062

Term of patent 14 years

Int. Cl. D6—06

U.S. Cl. D6—200

FIG. 1

FIG. 3

FIG. 1 is a rear perspective view of an adjustable headrest embodying my new design;

FIG. 2 is a front perspective view thereof; and

FIG. 3 is a sectional view along the horizontal center of the adjustable headrest.

I claim:

The ornamental design for an adjustable headrest, as shown and described.
